COMBINED BOTTLE AND SNAP-TYPE CLOSURE

Paul A. Marchant, Kansas City, Mo., assignor to Consolidated Thermoplastics Company, Los Angeles, Calif., a corporation of Delaware

Filed July 7, 1961, Ser. No. 65,850

Term of patent 14 years

(Cl. D58—6)

I claim:

The ornamental design for a combined bottle and snap-type closure, substantially as shown.
